UNITED STATES PATENT OFFICE.

GEORGE POINTON, OF TORONTO, ONTARIO, CANADA.

ABRADING DEVICE FOR GRINDING-MACHINES.

1,100,612.

Specification of Letters Patent. Patented June 16, 1914.

Application filed March 17, 1913. Serial No. 754,916.

To all whom it may concern:

Be it known that I, GEORGE POINTON, a subject of the King of England, residing at Toronto, in the county of York, Province 5 of Ontario, Canada, have invented certain new and useful Improvements in Abrading Devices for Grinding-Machines; and I do declare the following to be a full, clear, and exact description of the invention, such as 10 will enable others skilled in the art to which it appertains to make and use the same.

This invention relates to improvements in abrading devices for grinding machines.

One object of the invention is to provide 15 a device of this character having an abrasive surface constructed of a plurality of pieces of emery cloth or the like of such shape that they may be cut from narrow strips and scraps of material with very little waste 20 thereby affording a considerable saving of material and reducing the cost of renewing the devices.

Another object is to provide an abrading device having its abrasive surface 25 formed of small suitably shaped pieces of material smoothly and firmly secured thereto without forming blisters and which are so spaced from each other as to leave clearance channels between them.

30 With these and other objects in view, the invention consists of certain novel features of construction, and the combination and arrangement of parts as will be more fully described and claimed.

35 In the accompanying drawings; Figure 1 is a bottom plan view of an abrading device constructed in accordance with my invention; Fig. 2 is a side view thereof; Fig. 3 is a plan view of a strip of abrasive material 40 showing the manner in which the abrasive sections are cut therefrom for application to the disk and whereby the greatest number of sections may be cut from the strip with the least possible amount of waste.

45 My improved grinding device comprises a flat disk 1 which may be of any suitable shape and which is here shown as of circular form and as having a centrally disposed passage or socket 2 to receive the 50 means whereby the disk is fastened to the grinding machine. To the lower smooth and uninterrupted flat face of the disk is glued, cemented or otherwise firmly fastened sections 3 of abrasive material such as emery 55 cloth, paper or the like. The sections 3 may be of any suitable size and shape and any

desired number of sections may be provided for covering the working face of the disk. In the present instance the disk is shown as having secured thereto four sections or 60 pieces 3 of abrasive material, said sections or pieces being cut in sector shape and secured to the working surface of the disk as shown, whereby radial channels 4 are formed between adjacent sectors, leading 65 from the inner pointed ends 5 of the same, along and between their straight sides 6, to their outer edges 7 which are preferably coincident with the periphery 8 of the disk. These channels afford clearance for the particles which are ground off from the surface 70 of the object treated, and clearance for particles of the abrasive material itself. The sections 3 are furthermore cut in sector shape to facilitate the cutting thereof from 75 narrow strips M of material with the least possible amount of waste, as clearly shown in Fig. 3 of the drawings, and which enables the largest number of sections to be cut from the strip. I do not, however, wish to be 80 understood as confining myself exclusively to sector shaped sections as it is obvious that the sections may be formed in other shape, although I prefer that they have pointed inner ends 5 directed toward the center of 85 the device and I prefer that the channels 4 between the various sections shall be substantially radial and shall in no case grow smaller toward the periphery of the device. The obvious reason for this preference is 90 between the points 5 no space is left where the material might accumulate near the center, such as would be the case if the points were cut off on arcs struck around said center. The centrifugal force tending to drive 95 said material and the particles thereof toward the periphery of the disk, is of course least at the center of the device, and when such a space occurs there I find that the material is quite likely to accumulate. As for 100 the radial channels, if the device is constructed as shown and described these channels are of a uniform size throughout their length and are strictly radial. In any event I would have them approximately radial 105 and they should not grow smaller toward the periphery. The advantage of these channels is that in the rapid rotation of the device, the particles of the material acted on and the particles of the grinding surface 110 tend to flow outward along these channels by reason of centrifugal force. In applying the

sections to the disk it will also be obvious that the channels 4 will receive more or less of the glue or cement 9 which is pressed from beneath the sections, and the glue which is thus pressed out causes the edges of the sections to tightly adhere to the surface of the disk.

In forming the abrasive surface in a plurality of small pieces or sections, said sections may be secured to the face of the disk without blisters being formed which frequently occurs in devices of this character when the abrasive material is secured to the disk in one piece. The forming of the grinding surface in sections also permits one or more sections to be removed and replaced by new sections when they are worn, without requiring the removal and renewal of the entire abrading material as is necessary in the form of abrading devices now in use when one part of the abrading surface becomes worn before the other parts thereof.

From the foregoing description taken in

connection with the accompanying drawings, the construction and operation of the invention will be readily understood without requiring a more extended explanation.

Having thus described my invention, what I claim is:

The herein described abrading device comprising a disk having a flat surface and adapted to be rotated on its axis in the plane of said surface, and a series of sector-shaped sections glued to the face of said disk with their pointed inner ends slightly remote from the exact center thereof and their straight edges spaced from each other to form radial channels from said center to the periphery, for the purpose set forth.

In testimony whereof I have hereunto set my hand in presence of two subscribing witnesses.

GEORGE POINTON.
